United States Patent Office

Des. 186,760
Patented Dec. 1, 1959

186,760

BRUSH HEAD

Joseph A. Larson, Sparta, and Alfred F. Gabower,
Tomah, Wis., assignors to Sparta Brush Co., Incorporated,
Sparta, Wis., a corporation of Wisconsin

Application June 12, 1958, Serial No. 51,321

Term of patent 3½ years

(Cl. D9—2)

Fig. 1 is a perspective view of the bristled side of a brush head embodying our new design.

Fig. 2 is a perspective view of the upper side thereof.

Fig. 3 is an enlarged end elevational view thereof.

We claim:

The ornamental design for a brush head, as shown.
